[57] ABSTRACT

In a railroad car having relatively sliding doors, a lock device including a hasp pivotally mounted on a first door and having a loose fit therewith, said hasp having

an elongated shank and a free cam end the provided with a tapered diagonally extending bevel portion and a lower seal locking portion, a keeper housing including an enclosed hasp cam entry slot portion and a vertically open wedge receiving chamber portion and a seal and locking portion cooperative with the hasp portion for locking and sealing of the hasp when the hasp cam portion is within the hasp cam entry slot, and a vertically extending wedge locking pin extendable into the vertically opened wedge receiving chamber portion and having a complementary diagonally extending beveled edge portion for engagement with the bevel edge of the hasp, said wedge cam portion being stowed behind the hasp shank within the wedge locking pin chamber, said wedge pin having an upper portion above the bevel edge engageable with the keeper housing top to limit downward movement of the wedge pin and having a lower end portion engageable with a keeper mounted seat below the keeper wedge chamber, the lower end of said wedge pin further having an abutment engageable with the underside of said keeper housing to limit upward movement of said wedge pin, the engagement of the bevel edge of the wedge pin with the bevel edge of the hasp cam within the wedge pin chamber wedgingly preventing removal of the wedge pin and hasp from the keeper housing mounted on the other associated door of the car.

3 Claims, 3 Drawing Figures.

FIG.1

FIG.2

FIG.3

LOCK ARRANGEMENT FOR BOX CAR DOORS

BACKGROUND OF THE INVENTION

1. Field of the Invention

This invention pertains to the field of railroad cars having one or more sliding doors, as, for instance, with railroad box cars and, in particular, deals with locking devices for holding relatively sliding doors together and releasing same as, for instance, seen by U.S. Pat. No. 3,596,959 which is hereby incorporated herein by reference.

2. Description of the Prior Art

The prior art teaches the use of locking devices for relatively slidable doors of railroad box cars such as U.S. Pat. No. 2,788,995 but does not disclose a type of lock device to apply locking forces against a door hasp to insure positive wedging locking action of the two doors together in locked position. This is what the invention accomplishes.

BRIEF DESCRIPTION OF THE DRAWINGS

FIG. 1 is a partial view of the railroad car doors held in the locked position by the locked condition of the locking device;

FIG. 2 is sectional view taken along line 2—2 of FIG. 1;

FIG. 3 is a partial view of the railroad car doors wherein the locking device is shown in the partially disengaged position attendant to opening of the doors.

SUMMARY OF THE INVENTION

This invention relates to locking devices for relatively sliding doors of railroad box cars. The invention is for the wedge locking of the doors together by means of a diagonally double locking pin wedgingly holding the car door hasp in locked relation entailing the use of a wedge locking pin and hasp stowed within a keeper mounted on one of the doors. The keeper is also provided with a seat for supporting the locking pin in the unlocked position to permit removal of the hasp and its wedging cam from the keeper. The keeper and hasp are provided with further lock means and also seal means for the two locked-together doors. The invention, therefore, provides for diagonally extending double locking surfaces on the hasp and pin for securely holding of the hasp within the hasp keeper.

These and other objects will become more apparent from reference to the following description, appended claims and attached drawings.

DESCRIPTION OF THE PREFERRED EMBODIMENT

The lock mechanism for a sliding door assembly of a railroad car, as embodied in this invention, is of such construction to be utilizable for the double doors of a box car as well as for the single door of a box car. As seen from the drawings, the double doors of the box car comprise a first door 2 and a second door 4, these doors being mounted for sliding movement upon the side of the car. The door 2 is provided with a panel 6 and the door 4 is provided with a panel 8. The door 2 is also provided with a seal structure 10 which intermeshes with the seal arrangement 12 of the door 4.

The locking device 14 of the instant invention comprises a hasp or hinge member 16 which is held adjacent the seal structure 10 of the door 2 by the fixed pin 18 which is provided with a head or enlarged part 20

on a shaft part 22 and the head 20 is spaced a sufficient distance away from the mount surface 24 (see FIG. 2) to permit laterally inwardly and outwardly movement of the hasp so as to disengage the same from its keeper

5 26. The end 28 of the hasp 16 is provided with an elongated slot 30 which allows for longitudinal movement in a generally horizontal plane of the hasp relative to the shaft 22 to permit disengagement of the hasp from the keeper 26 when the wedge locking pin 32 is removed from the keeper 26. The hasp member is further provided with an elongated shank portion 34 and a cam or free end portion 36 which is provided with a downwardly and diagonally extending to the right beveled edge portion 38 which in the locked position of the 15 wedge pin and hasp cam engages complementally downwardly and diagonally extending to the right beveled edge 40 of the wedge locking pin 32 as viewed in FIGS. 1 and 3. The hasp cam bevel edge portion 38 is on the inner right back side of the hasp cam 36 adjacent the 20 shank portion 34 and the wedge pin bevel edge portion 40 is on the upper widened part 42 of the locking pin 32 intermediate its upper retainer abutment or stop 44 and its lower thinner shank portion 46 at the bottom of which is located bottom retainer abutment or stop 48. 25 Just inwardly of the cam portion 36 of the hasp 16 and depending therefrom is located a further locking and sealing portion 50 provided with a seal opening 52 and a lock receiving opening 54 which cooperate with the common or single seal receiving and lock receiving opening 56 on the lower lug portion 58 of the keeper 26. A sealing wire may be passed through the sealing opening 52 and the elongated hole 56 and a lock loop portion of a lock (not shown) may extend through the hasp lock opening 54 and the elongated hole 56 on the 30 keeper for respectively sealing and locking of the hasp to the keeper in the locked position of the hasp. The keeper arrangement 26 that is mounted on the door 4 just inwardly and adjacent the seal arrangement 12 includes a backing plate or bracket member 60 and a front or outer keeper bracket member 61 to define a wedge pin and hasp cam receiving portion or chamber 62. The front bracket 61 includes upper and lower horizontally extending bracket portions 64 and 66 defining an aperture or hasp cam entry opening 68. The top and bottom of the plates 60 and 61 define openings for extending of the wedge pin through the chamber 62 and the keeper further defines an end hasp cam receiving pocket 70 as defined by the backing plate 60 and the L-shaped or bent bracket portion 72 of the keeper 26. 40 The lower end of the bracket 60 is provided with an L-shaped wedge pin seat member 74 to support the lower end of the shank portion 46 of the wedge pin 32 as seen in FIG. 3.

55 The locking pin 32 is trapped in the keeper 26 because of the upper and lower abutments 44 and 48 engaging the upper and lower edges of bracket portions 64 and 66 of keeper 26. The locking pin as positioned in FIG. 3 permits the hasp member 16 to be moved into opening 68, chamber 62 and then into the pocket 70 to permit the locking pin 32 to be driven down into a wedged locking position by a hammer as shown in FIG. 1 where the bevel edges 38 and 40 are very tightly wedged against one another to prevent accidental movement of the locking pin. The vertically extending bevel edge 76 on the shank portion 46 initially allows guiding of the locking pin into the locking position when the hasp cam 36 is in the pocket 70. The wedge 60 65

pin 32 may be dislodged to an unlocked position as shown in FIG. 3 by an upward force directed by an instrument such as a hammer on one of its abutments 44 or 48 on its underside. The advantage of this novel arrangement is that it provides for easy access to the locking wedge pin for opening or closing with a hammer and, further, the locking cam of hasp 16 36 and the bevel edges 38 and 40 of both hasp 16 and pin 32 prevent accidental opening of the lock and the wedging action permits the door to be fully closed when locked. The loose fit of the hasp by its connection to the door permits easy movement of the hasp to the right and left and inwardly and outwardly as well as upward or downward movement about its pivot.

The foregoing description and drawings merely explain and illustrate the invention and the invention is not limited thereto, except insofar as the appended claims are so limited, as those skilled in the art who have the disclosure before them will be able to make modifications and variations therein without departing from the scope of the invention.

What is claimed is:

1. A device for locking relatively sliding doors of a railway car in a closed position, said device comprising a hasp one end of which is pivotally mounted to the front of a first door for multiplanar pivotal movement and having a shank and a cam-shaped free end provided with a rear bevel edge portion that extends downwardly of the hasp and inwardly towards the pivotally mounted end of said hasp, a keeper mounted on the front of the other door and being comprised of a backing means and a bracket element connected to said backing means, opposed portions of said bracket element and said backing means defining an opening for receiving the cam-shaped end of said hasp, the opposed portions of said bracket element and said backing means slidably engaging the cam-shaped end of said hasp when the cam-shaped end of said hasp is inserted in the hasp-receiving opening, upper and lower bracket means affixed to said backing means and arranged in operable and spaced relationship to said bracket element, and defining a locking pin receiving opening located between said backing means and said upper and lower bracket means and arranged contiguous to and in open communication with the hasp receiving opening,

a locking pin having left side, top and right side edges and being slidably received within the locking pin receiving opening, one of the left and right side edges of said pin having a bevel edge portion that extends downwardly of the top edge of said pin and inwardly toward the other side edge of said pin, the bevel edge portion of said one edge of said pin being complementary to and for engagement with the bevel edge portion of said hasp, and being disposed to the rear of the shank of said hasp while the complementary bevel edge portions of said hasp and said one edge of said pin are in wedging engagement when said pin is received in the pin-receiving opening of said bracket means,

said complementary bevel edge portions of said hasp and said one edge of said pin in conjunction with the cam-shaped end of said hasp and the opposed portions of said bracket element and said backing means being in cooperative wedging engagement for effecting locking and retaining of said doors in a closed position,

said locking pin including upper and lower portions for abutting said upper and lower bracket means so as to retain said pin within the pin receiving slot during use of said device,

said pin including a shank portion disposed beneath the bevel edge portion of said one edge of said pin, said shank portion of said pin having a bevel edge portion for initially engaging the bevel edge portion of said hasp when said hasp is connected to said keeper and said pin is in a raised position, and a seat means mounted on said keeper below said lower bracket means for supporting said shank portion of said pin and said locking pin in a raised position.

2. The invention according to claim 1 wherein said hasp and said keeper have cooperative portions for sealing and locking said device when the cam end of said hasp is between said bracket element and said backing means.

3. The invention according to claim 1 wherein said hasp has an elongated slot at its pivotally mounted end, such slot permitting longitudinal movement of said hasp relative to said keeper when said hasp is disengaged from said keeper.
